C. FRANZEL.

GRAIN SCALPER, SHELLER, AND PEELING MACHINE.

No. 426,796.

Patented Apr. 29, 1890.

UNITED STATES PATENT OFFICE.

CARL FRANZEL, OF DOMSTADTL, MORAVIA, AUSTRIA-HUNGARY.

GRAIN SCALPER, SHELLER, AND PEELING-MACHINE.

SPECIFICATION forming part of Letters Patent No. 426,796, dated April 29, 1890.

Application filed June 7, 1889. Serial No. 313,464. (No model.)

To all whom it may concern:

Be it known that I, CARL FRANZEL, proprietor of a factory, a subject of the Emperor of Austria, residing at Domstadt, Moravia, in 5 Austria, have invented certain new and useful Improvements in a Grain Scalper, Sheller, and Peeling-Machine; and I do hereby declare that the following is a full, clear, and exact description of the same, reference being made to the accompanying drawings, in 10 which—

Figure 1 shows a front view of my apparatus partially in transverse section and partially in elevation. Fig. 2 shows a section on the 15 line A B of Fig. 1. Fig. 3 shows a section on the line C D of Fig. 1. Fig. 4 shows a plan of the frame-work with its bracing rods and the bearings on a reduced scale. Fig. 5 shows an inside view of one of the clamping-rings 20 carrying the stone cylinder. Fig. 6 shows a transverse section of Fig. 5.

The principal new feature of the present invention is the substitution for the usual heavy millstone rotating in a casing closed 25 on all sides of a light cylindric grinder open on both sides, made of stone, stone-mass, or emery, which is mounted on a driving-shaft by means of annular clamping-rings, of a peculiar shape, holding said stone cylinders by 30 means of dovetailed notches. This stone cylinder grinds against a drum open on one side and covered with a perforated plate or wire-gauze and provided with a stationary lid or cover, whereon a regulating sliding plate is 35 arranged, which, provided with a slit, enables me to raise or lower the outlet, so that the treated product can be withdrawn at pleasure or as may be found necessary. Compared with the machines in use up to this 40 time, this arrangement presents the following advantages: In the first place, a considerably-smaller driving-force is required. In the second place, it works continuously without requiring the stone to be dressed anew 45 and combines therewith an increased efficiency for scalping and shelling grain or peeling barley, and in the third place it gives finer work and better results than the machines hitherto used.

As shown in Figs. 1 and 4, the driving-shaft *c* is carried by the standards *a a'*, which

are braced by the rods *b b' b'' b'''*, which are screw-threaded and held in position by nuts. On this shaft *c* a cylinder, open on both sides and made of stone, stone-mass, or emery *d*, is 55 keyed by means of clamping-rings *e*. These rings *e*, Figs. 5 and 6, carry at their periphery dovetail notches *e'*, engaging in similar dovetails in the stone cylinder, Fig. 1. Plates *e''* are arranged on the clamping-rings so as to 60 close the cavity of the stone cylinder *d*. The clamping-rings *e* and the plates *e''* are rigidly connected by means of bolts *e'''*, provided with nuts at their threaded ends.

Around the stone cylinder *d*, I arrange a 65 drum *l*, which is rigidly held together by means of a suitable number of bolts passing through the side pieces and the circumferential rim or cover, thus firmly connecting all the parts. This drum is lined all around with 70 a perforated plate or wire-gauze *z*. The drum *l* is provided with suitable bearings *p q*, one on each side. These bearings are hollow and cylindric in form and are sufficiently large so that they may surround the operating-shaft *c* without touching the same. The bearing-pieces *p* and *q* are secured to the side walls of the drum *l* by means of suitable 75 bolts and nuts, as clearly shown in Figs. 1 and 3. The drum *l* is supported by these 80 bearings on journals *r s*, arranged one on each side of the apparatus upon supporting-bars *t v*, to which they are bolted. The supporting-bars *t v* rest upon the rods *b b'*, which are secured to the standards *a a'*. The supporting-bars *t v* are secured in place upon the rods *b b'* by means of suitable pins or keys. 85

The outer end of the bearing *p* is covered by a plate *p'*, fitting loosely around the shaft *c* and bent outwardly at its upper end, thus 90 forming an inlet-passage *s*, which leads to the interior 12 of the drum.

On the bar *v* bolts *w* are riveted for holding the stationary cover *x*, which closes one side of the drum. On this stationary cover 95 *x* is secured the sliding plate *y*, which is arranged to move in guides formed in the cover and which is provided with the eccentric slot *z*, which forms the outlet-passage.

When the sliding plate *y* is moved or rotated to the right or left by means of the handle 1, the outlet is raised or lowered as 100

the slot z is turned in either direction, as will be seen in Fig. 2, which causes a larger or smaller amount of grain to accumulate in the drum before discharging, and this amount 5 can be regulated as desired by simply adjusting the sliding plate y . The sliding plate y may then be securely held in place by means of the binding-screws 10.

The movable drum l is inclosed in a stationary outer casing 11, fixed on the rods b and b' .

15 is a ring keyed on the shaft c , which closes the opening into the bearing q from the inside of the drum.

15 On the main shaft c are arranged two pulleys f and f' for the transmission of the motive power, and also the pulley g , which transfers power to the pulley m and the gear-wheel n , which gears with the toothed wheel 20 o , arranged on the drum l , and thus imparts to this drum a rotary motion inverse to that of the stone cylinder d and at the desired velocity. The drum l should make about sixteen revolutions per minute, while the stone 25 cylinder d makes in the same time from two hundred to two hundred and forty revolutions. On the other side of the shaft c the pulley h is arranged, transferring motion by

means of the pulley i to the axle k of the fan 7. The fan 7 removes, through the opening 30 g , the air entering by the air-holes 4, by the bottom-opening 5, and by the inlet and outlet, together with the grain-shells, the dust, &c., in the direction of the arrow, Fig. 1. The feeding of the grain to be treated takes 35 place through the opening of the bearing p , at 8, into the space 12, the outlet being on the opposite side through the opening z into the conduit 9.

Having fully described my invention, what I 40 claim as new, and desire to secure by Letters Patent, is—

In a grain scalper, sheller, and peeling-machine, the stationary cover x , with the regulating sliding plate y , and the eccentric slot 45 z , for increasing or diminishing the accumulation of the grain in the mill, as may be found necessary, substantially as heretofore shown and described.

In witness whereof I hereunto set my hand 50 in presence of two witnesses.

CARL FRANZEL.
